ATTORNEY.

UNITED STATES PATENT OFFICE.

CLINTON C. HANCOCK, OF PHILADELPHIA, PENNSYLVANIA.

NECK-SCARF.

SPECIFICATION forming part of Letters Patent No. 228,460, dated June 8, 1880.

Application filed March 8, 1880. (No model.)

To all whom it may concern:

Be it known that I, CLINTON C. HANCOCK, a citizen of the United States, residing in the city and county of Philadelphia, and State of Pennsylvania, have invented a new and useful Improvement in Neck-Scarfs, which improvement is fully set forth in the following specification and accompanying drawings, in which—

10 Figure 1 is a rear view of the neck-scarf embodying my invention. Fig. 2 is a rear view of a detached portion, the parts being separated.

15 Similar letters of reference indicate corresponding parts in the several figures.

My invention relates to a neck-scarf known as a "long" scarf, adapted to be worn with a lay-down collar; and it consists in constructing the head of the scarf of two pieces, forming 20 a V or bifurcation, and inserting a bifurcated shield thereinto, in such manner that it rests snugly in position. The fabric of the head is not gathered or wrinkled, and the two pieces of the head cross each other and continue as 25 or form continuations of the aprons, as will be hereinafter set forth and definitely claimed.

Referring to the drawings, A represents the head of a neck-scarf, and B the aprons thereof.

The head is formed of two pieces, a a', and 30 each piece is connected to or continuous of one of the aprons B. Each piece is lined on the back, the pieces and linings forming pockets b b'.

The two pieces a a' are applied to each other, 35 and crossed and properly united by stitching, and, if desired, a ring or other ornamentation may be pinned to the scarf to cover said stitching.

The lining of each piece a or a' is continuous 40 of the lining of the respective apron. The stitches of the piece a are cut, as at c, to form an inlet to the pocket b. The fabric or lining of the piece a' is cut at or about a right angle to the line of the length of the piece a', to 45 form an inlet, c', to the pocket b'; but in other respects the pockets b b' are properly and neatly closed and connected to the pieces a a' by machine or other stitching.

C represents a V-shaped or bifurcated shield, one limb of which is inserted through the inlet c into the pocket b, and the other limb is inserted through the inlet c' into the pocket b', thus bracing and supporting the two pieces a a' or head A. The lining of the piece a is now drawn over the inlet c', so as to conceal and 50 cover the same, and properly stitched to the lining of the piece a', this operation also closing the inlet c. When the fastening-loop d is drawn through the lining of the piece a the scarf is 55 complete.

It will be seen that I produce a neck-scarf adapted for lay-down collars, having a head which sets well under the collar, similar to a scarf having a neck-band, and is crossed. There is no gathering or wrinkling of the 60 scarf fabric either in front or rear of the angle of the V, and, while the head is formed of two separate pieces, the shield, with two limbs, is formed of one piece of suitably stiff material, and thus well sustains the head and preserves 65 its shape.

Having thus described my invention, what I claim as new, and desire to secure by Letters Patent, is—

1. The V-shaped shield in one piece, in combination with the head A, formed of two separate pieces, a a', and the aprons B, continuous of said pieces, substantially as and for the purpose set forth. 75

2. The V-shaped shield, in combination with the head A, composed of lined pieces a a', forming pockets b b', the pocket b having an inlet, c, and the pocket b' an inlet, c', both inlets being closed by the lining of the piece a, substantially as and for the purpose set forth. 80

3. The neck-scarf consisting of the aprons B, the head A, composed of crossed pieces a a', the pockets b b' whereof have inlets c c', and the V-shaped shield C, all constructed, combined, and operating substantially as and for 85 90 the purpose set forth.

C. C. HANCOCK.
